NEW YORK.

COMBINED CONTROL AND BRAKE FOR SEWING-MACHINES.

1,279,763.

Specification of Letters Patent. Patented Sept. 24, 1918.

Application filed July 12, 1918. Serial No. 244,671.

To all whom it may concern:

Be it known that we, PAUL P. RUHE and WILLIAM A. SONEN, both citizens of the United States, and residents, respectively, of Hoboken, in the county of Hudson and State of New Jersey, and Brooklyn, in the county of Kings and State of New York, have invented new and useful Improvements in a Combined Control and Brake for Sewing-Machines, of which the following is a specification.

Our invention relates to improvements in power transmitting constructions for sewing machines, and has for a main object the provision of a combined control and brake which may be used in connection with power operated sewing machines, wherein an electric motor and a rheostat for regulating the current are employed, and wherein a vertical treadle operated shaft is arranged as an element through which to control the operation of the rheostat, and by which, simultaneously with the deenergization of the rheostat to effect a direct braking action on the motor shaft braking pulley.

A further object of our invention is to provide a novel casing for the accommodation and support of the working parts in compact arrangement so as to take up just as little space as possible consistent with the objects in view; to provide the casing with novel detachable doors to one of which the rheostat is secured; and also to provide a standard or support of simple construction, to which the casing as a whole with the parts associated therewith may be quickly and readily attached and detached.

With these objects in view and others, the invention resides in the details of construction and in the arrangement and combination of parts hereinafter described, defined in the claims, and illustrated in the accompanying drawings, forming a part of this specification; and it will be understood that changes and alterations in the precise embodiment of the invention herein disclosed, may be made, to which changes and alterations the inventors are entitled, provided the same are effected within the scope of what is claimed.

In the accompanying drawings:- Figure 1 is a side elevational view of our device, together with the operating means therefor, the same being here shown as supported upon a standard.

Fig. 2 is a vertical sectional view, taken in the direction of line 2-2 of Fig. 1.

Fig. 3 is a cross sectional view, taken in the direction of line 3-3 of Fig. 1.

Fig. 4 is a similar view, taken in the direction of line 4-4 of Fig. 1.

Fig. 5 is a detail view of the rheostat.

The present embodiment of the invention is shown in connection with a standard or support designed for use either as one of the standards for any common type of sewing machine or for a worktable or bench of the character used in factories for the support in consecutive order of a plurality of sewing machines.

The standard consists of a casting having a bottom cross piece 6, formed at each end with a downwardly extending offset foot 7, and having parallel upright side members 8 and 9, all formed in cross section like an angle-iron as best shown in Fig. 1. A distance below their top ends, the upright members 8 and 9 are each cast with an enlarged inwardly projecting portion 10 having formed upon its top end a ledge or flange 11. 70

The casing includes the parallel side plates 12 and 13, a bottom plate 14, and a top plate 15, the said side plates 12 and 13 extending upwardly for a distance beyond the top plate 15 and having their ends 16 bent outwardly 75 at right angles so as to be adapted to lie flat upon the ledges 11, for the support of the casing in a position depending from the projections 10 and between the same. One of the side plates, herein shown as side plate 12, 80 is made with an outward deformation 17, provided with inlets as 17', to allow the entrance of air for cooling the rheostat. Laid flat upon the horizontal end portions 16 is a bridge plate or platform 18, upon which is 85 bolted the motor 19. The ends 16 together with the bridge plate 18 are removably secured to the ledges 11 by means of bolts 20 and securing nuts 20'.

The two remaining sides of the casing are 100 removable and consist of door plates 21 and 22 of such extent as to lie flat against the edges of the side plates 12 and 13, and of the bottom plate 14 and the top plate 15. To secure these removable doors in position, 105 there are provided in the bottom plate 14 spaced from the opposite edges thereof, recesses as 23, receptive of the ends of the curved arms 24 formed integral with said doors. The top ends of the doors are 110

snapped behind hooked detents 25 formed on the opposite ends of the spring plate 26, which extends across the top plate 15 and is secured thereto by screws as 27 (Fig. 3).

Arranged to reciprocate vertically through suitable openings provided in the bottom 14, and top 15, midway their length, is a shaft 28, the upper end 29 of which is bent outwardly and upwardly (Fig. 2) at an angle, terminating in a flat vertical end 30, to which is riveted the reduced end 31 of the shoe or brake plate 32. The top end of this shoe is formed arcuate and beveled crosswise to engage the V-shaped recess 33, provided in the periphery of the driving pulley 34, which is fast upon the motor shaft 35. Engaged in the adjacent peripherical recess 36 of the driving pulley is the belt 37 by which motion is imparted to the machine in the usual way. Below the bottom plate 14, the shaft 28 is reduced to a flat surface 38 to accommodate the end of the lever 39, the said end being provided with a slot 40, in which works a pin 41 projecting from the face 38, and by which operative connection is provided.

The opposite end of the lever 39 is pivoted at 42 to the inner side of the upright 9. Pivotedly engaged with this lever at 43, intermediate its length, is an angular link 44 provided with a pin 45 projecting therefrom at right-angles. Secured to this pin at 46 is the rear end of a foot treadle 47, which is formed near its forward end with down-turned spaced ears or lugs 48, rockably journaled upon a shaft 49. This shaft 49 may rigidly project from the bottom cross member or connect like parts of two adjacent standards. Mounted around the shaft 49 between the ears 48 is a spiral spring 50, having one end connected with said shaft and the other end extending rearwardly underneath the foot treadle in such manner as to normally hold the foot treadle in elevated position with the shoe 32 in firm engagement with the braking face of the driving pulley.

Within the casing there is transversely secured to but insulated from the shaft 28 a conducting plate 51, the rear end of which is offset toward the door plate 21, and terminates in a head 52 adapted to receive a carbon 53, against the rear end of which presses a spring 54, riveted at 55 to said plate 51, in such manner as to hold said carbon in position for engagement with a series of contacts or buttons which project in close vertical alinement from the inner side of the rheostat 56. The rheostat is supported at its corners upon posts 57 carried by the door plate 21. Of the contacts, the first two 58, from the top, are without electrical connections, while the remaining contacts 59, herein shown as 4 in number, are provided with electrical connections in the

usual way to pass the current to terminal contact 60, arranged near the top right-hand side of the rheostat device. Terminal contact 60 projects in position to be engaged by a detent conductor 61, secured to the underside of the binding post 62, arranged in but insulated from the top plate 15. To another binding post 63, similarly arranged in the top plate, is connected on the underside thereof a resilient conductor 64, which connects with a curved arm conductor 65, carried by the transverse plate 51. This whole arrangement is such that when the foot treadle 47 is depressed to withdraw the shoe 32 from the driving pulley, the conducting plate 51 will draw the carbon 53 across the ends of the contact buttons 59 for energizing the motor 29. The electric connections from the buttons 59 are obviously different as may be necessary to regulate the velocity of the current, so that the motor may operate in four different speeds. Thus when the carbon engages the first top button 59, the machine will be driven at a certain speed; when it engages the second a higher speed will be obtained; and so on, each successive button toward the bottom producing an increase in speed. Two non-electrically connected buttons 58 are provided in order to have a contact support for the carbon until the shoe 32 is wholly withdrawn from the driving pulley.

The current may be traced from a source of power as P through a wire 66 to the motor 29, from the motor through a wire 67 to the binding post 63, thence through the resilient conductor 64, arm 65, transverse plate 51, carbon 53, buttons 59, the return current being effected through terminal contact 60, detent 61, binding post 62, and wire 68 back to the source of power.

From the foregoing description taken in connection with the accompanying drawings, it will be manifest that under the depression of the foot treadle 47, the brake shoe 32 will be drawn away from the driving pulley, and that simultaneously therewith the carbon will be carried downwardly into engagement with the rheostat buttons to operate the motor and consequently the machine, the rapidity of operation depending upon the degree of the depression of the foot treadle. It will also be seen that immediately pressure is removed from the treadle 47 the spring 50 will reposition the parts, bringing the carbon into engagement with the non-conducting buttons and simultaneously therewith forcing the brake shoe 32 into engagement with the driving pulley for bringing the mechanism instantly to rest.

Having thus described our invention, what we claim is:—

1. In a sewing machine standard in combination, spaced-apart confronting ledges, a casing having opposing side plates extend-

ing above its top plate to engage over said ledges, a removable door plate combined with said casing, a rheostat bolted to the inner side of said removable door plate and 5 provided with a series of contacts in vertical arrangement, a vertically reciprocable shaft extending through said casing in alinement with said contacts, a transverse conducting plate carried by but insulated from said 10 shaft, conductor means carried by said transverse plate adapted to engage said contacts in succession, treadle operated means carried by the standard for reciprocating said shaft, a motor having a brake pulley 15 mounted upon said side members over said ledges, a shoe carried by said shaft to engage and disengage said brake pulley, connections to complete a circuit through said motor, said transverse conducting plate, and 20 said rheostat, the circuit being opened and closed accordingly as said shaft is actuated for the engagement and disengagement of said shoe with said brake pulley.

2. In a device of the class described, a 25 casing having its opposed side members extending above its top plate and adapted to sustain the casing in depending position, a removable door plate for said casing, a rheostat bolted to the inner side of said door 30 plate and provided with a series of contacts arranged in vertical alinement, a pair of binding posts arranged in but insulated from the top plate of said casing, a vertically movable shaft extending through the 35 top and bottom plates of said casing in alinement with said contacts, a transverse conducting plate carried by but insulated from said shaft, conductor means removably engaged with said transverse plate for making 40 contact with said buttons in succession accordingly as said shaft is actuated, a resilient conductor between one of said binding posts and said transverse conductor, a terminal contact carried by said rheostat, a 45 conducting detent carried by the other binding post and adapted to engage said terminal contact when said movable door is applied, a motor, means for connecting said binding posts in circuit with the motor and 50 source of current supply, and spring pressed

treadle operated means connected with the lower end of said shaft whereby to actuate the same to effect engagement with the contacts in succession, said spring pressed treadle operated means normally holding said shaft 55 with the conductor means out of engagement with said buttons.

3. In a device of the class described, a casing having its opposed sides prolonged beyond its top plate and a pted to act as 60 hangers for the support of the casing in depending position, recesses cut in the top surface of the casing bottom plate spaced from the opposed edges thereof, opposed removable door plates adapted to lie flush against the edges of the casing side plates and the top and bottom plates thereof and provided with inwardly curved arms formed to enter said recesses for the support of the door plates upon the said bottom plate, a spring 70 plate secured across the top plate and formed with detent ends behind which the removable door plates may be snapped against displacement, a rheostat bolted to the inner side of one door plate, a pair of 75 binding posts carried by but insulated from the top plate of said casing, a detent conductor carried by one binding post, a terminal contact carried by said rheostat to engage said detent when the door plate is set 80 in position, a series of contacts carried by said rheostat in vertical arrangement, a vertical reciprocable shaft extending through said casing in alinement with said contacts, a transverse conducting plate carried by but 85 insulated from said shaft and adapted to make engagement with said buttons in succession accordingly as the shaft is actuated, a resilient conductor connected between the other binding post and said transverse plate, 90 and connections with said binding posts to close a circuit whenever the shaft is actuated to effect engagement between said transverse conducting plate and any one of said rheostat contacts. 95

In testimony whereof we have signed our names to this specification.

PAUL P. RUHE.
